D. C. DAVIS

DEVICE FOR CONTROLLING THE FLOW OF FLUIDS

Filed August 13, 1923

UNITED STATES PATENT OFFICE.

DAVID C. DAVIS, OF CHESTER, PENNSYLVANIA, ASSIGNOR TO WESTINGHOUSE ELECTRIC AND MANUFACTURING COMPANY, A CORPORATION OF PENNSYLVANIA.

DEVICE FOR CONTROLLING THE FLOW OF FLUIDS.

Application filed August 13, 1923. Serial No. 657,944.

My invention relates to devices for controlling the flow of fluids, more particularly to devices which shall automatically control the flow of the fluids concurrently with the periodic operation of any designated electrically energized mechanism, as for example, a motor, and it has for an object to provide apparatus of this character which shall be of simple and rugged construction and which shall positively control the flow of the fluid coincident with the energizing and de-energizing of the electrical mechanism.

These and other objects, which will be made apparent throughout the further description of the invention, may be attained by the employment of the apparatus herein-after described and illustrated in the accompanying drawing in which the single figure 20 is a diagrammatic illustration of one form of device in which my invention may be practiced.

Described generally, the invention resides in actuating a cock or valve of any well-known construction by the movements of two solenoids, one solenoid being arranged to open the valve while the remaining solenoid is arranged to close the valve. Upon electrical current being transmitted to the device, the first solenoid is momentarily energized and moves to open the cock to permit the flow of the fluid. This solenoid also actuates a current control device which places the motor in circuit with a source of electrical energy. The fluid is permitted to flow through the valve until such time as the closing solenoid is energized, whereupon the valve is closed and the motor is disconnected from the circuit.

Referring to the drawing for a more detailed description of my invention, I show a motor 10 and a valve 11. The valve 11 may be of any well-known construction which is adapted to be opened and closed as by an operating lever 12. The free end of the operating lever 12 is secured to an arcuate arm 13 having disposed at one end an opening solenoid 14, and at its remaining end a closing solenoid 15. A spring 16 is connected to the operating lever 12 and to a fixed point 17, which is located some distance below the center line of the cock 11. It is installed under tension and is so arranged as to bias the operating lever 12 to either a closed or an open position, thereby mini-

mizing any tendency for the lever to come to rest in a midway position, such as illustrated on the drawing.

The solenoids 14 and 15 include, respectively, core members 18 and 19 which are secured to the ends of the arcuate arm 13. Arranged concentrically about the core members are the respective coils 20 and 21. One terminal of each of the solenoid coils 20 and 21 is connected through conductors 22 and 23 to the respective fixed contact points 24 and 25 of a two-way switch 26, the blade of which is in turn connected through a conductor 27 to the one side 28 of a supply circuit. The switch 26 may be operated in any desired manner, that is, manually or by automatic means.

Associated with the solenoid coil 20 is a current control device 29 embodying resilient springs 30 and 31 which are joined by a non-conducting element 32. The coil 20 is connected to the spring 30 while the spring 31 is connected through a conductor 33 to the side 28 of the supply circuit. The free ends of the springs 30 and 31 are mounted to engage fixed contact members 34 or 35, respectively. The springs 30 and 31 are normally biased upward as shown. The contact member 34 is connected through a conductor 37 to the opposite side of the supply circuit at 38, while the contact member 35 is connected through a conductor 39 to one terminal 40 of the motor 10.

The other terminal 40' of the motor 10 is connected through a conductor 41 with a fixed contact member 42 adapted to engage a spring 43 which, together with a similar spring 44, form a current control device 45 which is in general, a duplicate of that at 29 except for the fact that the fixed contact member 51 for the lower spring is mounted thereover rather than thereunder. The spring 43 is connected through conductors 47 and 48 to the side 38 of the supply circuit. The spring 44 is connected through a conductor 49 to the solenoid coil 21, while its remaining end may engage a fixed contact member 51 which is connected through a conductor 52 and the conductor 48 to the side 38 of the supply circuit.

The core 18 carries an extension 36 to engage the springs 30 and 31 and the core 19 carries a similar extension 46 to engage the springs 43 and 44.

The operation of the above device is as

follows: Upon the switch 26 being closed at the contact 24, a circuit is formed and the current flows from the side 28 of the circuit to energize the coil 20 of the opening solenoid 14, thence through the spring 30 and, by means of the contact 34 and the conductor 37, to the side 38 of the supply circuit. Upon sufficient magnetic influence being exerted, the core member 18 together with the 10 arcuate arm 13, the core member 19 and the operating lever 12 are moved in a clockwise direction a sufficient distance to fully open the valve 11 to permit the fluid to flow therethrough. The motion of the operating 15 lever 12 is accelerated by the spring 16, the tension upon which is gradually reduced as the operating lever is moved from its mid-position.

Upon the extension member 36 engaging 20 the current control device 29, contact is broken at the member 34 and established at the member 35, de-energizing the solenoid 14 and energizing the motor 10. Current flows from the motor to the side 38 of the 25 circuit by means of the conductor 41, the spring 43, and the conductors 47 and 48. The motor is continually energized and the operating lever 12 remains in such a position as to permit the fluid to flow through the 30 valve 11 until such time as contact is established at 25 in the switch 26. Current then flows through the conductor 23 to energize the coil 21 of the closing solenoid 15, from whence it flows through the conductor 49, 35 the spring 44, and the conductors 52 and 48 to the side 38 of the supply circuit.

Upon the coil 21 becoming energized, the core member 19 together with the arcuate arm 13, the core member 18 and the operating lever 12 are moved in a counter-clockwise direction a sufficient distance to fully close the valve 11, thereby shutting off the flow of the fluid and permitting the spring 31 to return to its normal position and open 40 the circuit to the motor. Upon the extension 45 striking the current interrupter 45, the springs 43 and 44 are disengaged from the contact members 42 and 51, breaking the motor circuit and also breaking the circuit 50 of the closing solenoid coil, thereby de-energizing the solenoid and permitting the device to remain inactive until such time as contact is re-established at 24, whereupon the cock is opened to permit the flow of the 55 fluid and coincident therewith current is permitted to flow to energize the motor.

As may be ascertained from the above description, the closing solenoid 14 and the current control device 29 form a positive 60 closing means for the motor circuit, while the opening solenoid 15 and the current control device 45 form a positive opening means for the motor circuit, thereby insuring the making and breaking of the contacts regard- 65 less of any tendencies toward adhesion of

the engaging elements. Furthermore, the closing of the motor circuit is arranged instantaneously with the opening of the valve, any possibility of the valve opening lagging behind the starting of the motor, being eliminated. In addition to the above, it may be noted that the solenoids are only energized momentarily, the amount of current consumed thereby being reduced to a minimum.

Apparatus of the character described 70 herein is especially adapted for use in connection with compression refrigerations of the household type which employ water as a condensing medium. Refrigerators of this type usually operate intermittently; 80 that is, a period of operation of from one to one and one-fourth hours is followed by a period of inactivity of from one and one-half to two hours, the length of the periods depending upon the duty imposed upon the 85 refrigerator and upon the setting of the automatic devices which control the switch for starting and stopping the motor. The amount of water employed is rather an important item in the operating costs of apparatus of this character. I have found, that with the use of the fluid control device here above described, a positive and complete opening and closing of the water control valve is accomplished coincident with the 90 starting and stopping of the motor, thereby avoiding any excessive use of condensing water and incidentally reducing the operating costs materially.

While I have shown my invention in but 100 one form, it will be obvious to those skilled in the art that it is not so limited, but is susceptible of various other changes and modifications, without departing from the spirit thereof, and I desire, therefore, that 105 only such limitations shall be placed thereupon as are imposed by the prior art or as are specifically set forth in the appended claims.

What I claim is:—

1. In a device for controlling the flow 110 of fluid, the combination of motor means, a valve, and electro-magnetic means for operating the valve coincident with the starting and stopping of the motor means, said means being de-energized except at the instant of starting or stopping.

2. In a device for controlling the flow of 115 fluid, the combination of a motor, a valve, and electro-magnetic means for opening and closing the valve coincident with the starting and stopping of the motor, said electro-magnetic means being energized only during opening or closing of the valve.

3. In a device for controlling the flow of 120 fluid, the combination of a motor, a valve, an electro-magnetic device for opening the valve and placing the motor in circuit with a source of electrical energy, and a second 125 electro-magnetic device for closing the valve

and for disconnecting the motor from the source of electrical energy.

4. In a device for controlling the flow of fluid, the combination of a motor, a current control device arranged in series with the motor and a source of electrical energy, electro-magnetic means for operating the valve and for actuating the current control device, whereby the valve is opened and closed coincident with the starting and stopping of the motor, said electro-magnetic means being energized only during the operation of the valve.

5. In a device for controlling the flow of fluid, the combination of a valve, a motor, a current control device arranged on each side of the motor, said current control devices being arranged in series with the motor and a source of electrical energy, an opening solenoid and closing solenoid for actuating, respectively, the current control devices and for operating said valve, and means for energizing and de-energizing the solenoids.

6. In a device for controlling the flow of fluid, the combination of a motor, a valve, a lever for operating the valve, a solenoid for moving the lever to close the valve, a solenoid for moving the lever to open the valve, a current control device associated with each solenoid, said current control devices being arranged in series with the motor and a source of electrical energy, and means for energizing either one of the solenoids, whereby the valve is actuated, and the motor is connected or disconnected to a source of electrical energy.

7. In a device for controlling the flow of fluid, the combination of a motor, a valve, a lever for operating the valve, a solenoid for moving the lever to close the valve, a solenoid for moving the lever to open the valve, means for biasing the lever to an opened or closed position, a current control device associated with each solenoid, said current control devices being arranged in series with the motor and a source of electrical energy, and means for energizing either one of the solenoids, whereby the valve is actuated, and the motor is connected or disconnected to a source of electrical energy.

8. In a device for controlling the flow of fluid, the combination of motor means normally energized, a valve, electro-magnetic means for actuating the valve, and means for temporarily energizing the electro-magnetic means to actuate the valve coincident with the starting of the motor means.

9. In a device for controlling the flow of fluid, the combination of a motor, a valve, electro-magnetic means for opening the valve, electro-magnetic means for closing the valve, means for momentarily energizing the opening electro-magnetic means coincident with the starting of the motor, and means for momentarily energizing the closing electro-magnetic means coincident with the stopping of the motor.

In testimony whereof, I have hereunto subscribed my name this 2nd day of Aug. 1923.

DAVID C. DAVIS.

and for disconnecting the motor from the source of electrical energy.

4. In a device for controlling the flow of fluid, the combination of a motor, a current control device arranged in series with the motor and a source of electrical energy, electro-magnetic means for operating the valve and for actuating the current control device, whereby the valve is opened and closed coincident with the starting and stopping of the motor, said electro-magnetic means being energized only during the operation of the valve.

5. In a device for controlling the flow of fluid, the combination of a valve, a motor, a current control device arranged on each side of the motor, said current control devices being arranged in series with the motor and a source of electrical energy, an opening solenoid and closing solenoid for actuating, respectively, the current control devices and for operating said valve, and means for energizing and de-energizing the solenoids.

6. In a device for controlling the flow of fluid, the combination of a motor, a valve, a lever for operating the valve, a solenoid for moving the lever to close the valve, a solenoid for moving the lever to open the valve, a current control device associated with each solenoid, said current control devices being arranged in series with the motor and a source of electrical energy, and means for energizing either one of the solenoids, whereby the valve is actuated, and the motor is connected or disconnected to a source of electrical energy.

7. In a device for controlling the flow of fluid, the combination of a motor, a valve, a lever for operating the valve, a solenoid for moving the lever to close the valve, a solenoid for moving the lever to open the valve, means for biasing the lever to an opened or closed position, a current control device associated with each solenoid, said current control devices being arranged in series with the motor and a source of electrical energy, and means for energizing either one of the solenoids, whereby the valve is actuated, and the motor is connected or disconnected to a source of electrical energy.

8. In a device for controlling the flow of fluid, the combination of motor means normally energized, a valve, electro-magnetic means for actuating the valve, and means for temporarily energizing the electro-magnetic means to actuate the valve coincident with the starting of the motor means.

9. In a device for controlling the flow of fluid, the combination of a motor, a valve, electro-magnetic means for opening the valve, electro-magnetic means for closing the valve, means for momentarily energizing the opening electro-magnetic means coincident with the starting of the motor, and means for momentarily energizing the closing electro-magnetic means coincident with the stopping of the motor.

In testimony whereof, I have hereunto subscribed my name this 2nd day of Aug. 1923.

DAVID C. DAVIS.

Certificate of Correction.

It is hereby certified that in Letters Patent No. 1,602,886, granted October 12, 1926, upon the application of David C. Davis, of Chester, Pennsylvania, for an improvement in "Devices for Controlling the Flow of Fluids," errors appear in the printed specification requiring correction as follows: Page 3, lines 53 and 54, claim 8, strike out the words "normally energized", and line 55, after the word "means", first occurrence, insert the words *normally de-energized*; and that the said Letters Patent should be read with these corrections therein that the same may conform to the record of the case in the Patent Office.

Signed and sealed this 14th day of December, A. D. 1926.
